UNITED STATES PATENT OFFICE

162,388

GLASS WASHER

Thomas H. Corbett, Chicago, Ill.

Application November 18, 1949, Serial No. 6,115

Term of patent 14 years

(Cl. D49—1)

To all whom it may concern:

Be it known that I, Thomas H. Corbett, a citizen of the United States, residing at Chicago, in the county of Cook and State of Illinois, have invented a new, original, and ornamental Design for a Glass Washer of which the following is a specification, reference being made to the accompanying drawing, forming a part hereof.

The drawing is a front perspective view of a glass washer showing my new design.

The side not shown is substantially the same as the one shown; and the back is substantially plain.

I claim:

The ornamental design for a glass washer, substantially as shown and described.

THOMAS H. CORBETT.
